UNITED STATES PATENT OFFICE

LAWRENCE L. NEEBE, OF WOODBURY, NEW JERSEY

SAFETY DEVICE FOR COUPLER POCKETS

Application filed July 8, 1931. Serial No. 549,537.

My invention relates to certain improvements in means for holding a coupler pocket to the bumper of a locomotive tender or car in case the bolts securing the pocket to the bumper should stretch or fail. This object I attain in the following manner, reference being had to the accompanying drawing, in which:

Fig. 1 is a plan view of a bumper and the 10 coupler pocket secured thereto;

Fig. 2 is a front elevation; and

Fig. 3 is a side elevation.

In the present instance, 1 is the bumper of a locomotive or tender. 2 is a coupler pocket 15 having flanges 3 at each side which are secured to the bumper by bolts 4. These bolts extend through vertical slots 5 in the pocket 2, so that the pocket can be raised or lowered to allow the coupler pocket to be shifted 20 in order to maintain the proper height of the pocket from the rails. 6 are plates welded to the underside of the bumper at X. These plates act to temporarily support the coupler pocket until repairs are made to the bolts, 25 should the bolts stretch or fail.

In order to hold the pocket in the event of the stretching or failing of the bolts that secure the pocket to the bumper, lugs 7 are cast integral with the bumper, and have inturned 30 ends 8 which overlap the flanges 3 of the pocket. The bolts draw the flanges of the pocket firmly against the bumper, and the lugs are free of the pocket, as shown in Fig. 1, but in the event of stretching or breaking of 35 the bolts the flanges of the pocket come in contact with the portions 8 of the lugs, which hold the pocket until repairs are made. In the present instance these lugs are cut away at 40 9 to allow the free turning of the bolts 4. The lugs extend preferably the full depth of the flanges of the pocket, so as to form a very substantial support for the pocket.

I claim:

1. The combination of a bumper of a railway vehicle; a coupler pocket; bolts securing the coupler pocket to the bumper; and lugs cast integral with the bumper and extending over a portion of the pocket, acting 45 as safety devices to retain the coupler in posi-

tion in the event of the stretching or failing of the bolts.

2. The combination of a coupler pocket having lateral flanges; bolts extending through openings in the flanges and extending into the bumper; and integral lugs on the bumper on each side of the coupler pocket, said lugs having inwardly extending portions which overlap the flanges of the coupler pocket. 55

3. The combination of a bumper of a railway vehicle; a coupler pocket having a flange at each side thereof, said flanges having vertical slots therein; bolts extending through the slots and into the bumper, said bolts securing the pocket to the bumper; and extended lugs cast integral with the bumper and located at each side of the pocket and having inwardly projecting ends overlapping the flanges of the bumper, said ends being recessed opposite the bolts to allow the bolts to be freely turned. 65 70

4. The combination of a bumper; a coupler head; bolts securing the coupler head to the face of the bumper; lugs at each side of the 75 coupler head overlapping portions of the coupler head but clearing the coupler head when the bolts are tightened; and plates welded to the underside of the bumper and extending under the rear portion of the coupler head. 80

5. The combination of a bumper of a railway vehicle; a coupling pocket secured to the bumper and lugs on the bumper extending over portions of the pocket, acting as safety 85 devices to retain the coupler in position in the event of the failure of the securing devices of the coupler.

LAWRENCE L. NEEBE.
